UNITED STATES PATENT OFFICE.

PAUL H. HENKEL, OF ERIE, PENNSYLVANIA, ASSIGNOR TO CONTINENTAL RUBBER WORKS, OF ERIE, PENNSYLVANIA, A CORPORATION OF PENNSYLVANIA.

BOX MOLD.

Application filed January 6, 1928. Serial No. 244,842.

The invention is designed to provide a means through which boxes formed of plastic material may be supplied with an opening which may be closed by a transparent plate. In many containers, such as battery boxes, it is desirable to have a means for indicating the condition of the battery liquids and such a transparent wall makes this possible. Features and details of the invention will appear from the specification and claims.

A preferred embodiment of the invention is illustrated in the accompanying drawings as follows:

Fig. 1 shows a side elevation, partly in section, of a press for forming a box.

Fig. 2 a plan view of the plate and the mold.

Fig. 3 a side elevation of one of the mold plates.

Fig. 4 a section on the line 4—4 in Fig. 3.

Fig. 5 a perspective view of the mold plates partly separated showing a box in place therein.

Fig. 6 a view of the mold plates with a part partially removed.

Fig. 7 a similar view with this part completely removed.

Fig. 8 a detached perspective view of a mold part.

Fig. 9 a plan view of a box wall.

Fig. 10 a section on the line 10—10 in Fig. 11.

Fig. 11 an elevation of one of the sides of the box.

1 marks the press base, 2 the ram cylinder, 3 the ram, 4 the ram platen, 5 the mold comprising a mold cavity, 6 passages in the platen for cooling, or heating fluid, 7 a cavity in the mold walls communicating with the cavity 6, 8 a press head, 9 straining rods running from the base to the head, 10 mold cores, 11 passages through the cores for heating, or cooling fluid, 12 a hydraulic cylinder on the head, 13 a pipe supplying fluid to the cylinder 12, 14 a piston in the cylinder, 15 a thrust rod extending from the piston against the mold, 16 a bottom plate of a mold lining system, 17 side plates of such a system, the bottom plate having a surrounding groove 18 receiving tongues 19 in the lower edges of the side plates. The bottom plate has a knock-out pin 20 which is adapted to engage a stop 21 slidingly mounted in the frame. The stop slide is

operated by a lever 22, the slides being connected by a rod 23. These parts are, or may be, so far as described substantially the same as the parts shown and described in the patent to John F. Allen, #1,549,177, 60 Aug. 11, 1925.

It is desired to form one wall 24 of a battery box with an opening 25 therethrough and with a surrounding slot 26, the sides of the slot having channels 27, this slot and channels extending through the top wall of the box so that a glass plate 28 may be dropped into the slot and sealed therein. A rib 25^a may surround the opening 25.

An opening forming projection 29 extends inwardly from a plate 17^a. It is of a contour to form the opening 25 and of sufficient length to contact the wall of the core when the core is in the mold cavity. Grooves 30 are formed in the plate, which 75 grooves are adapted to form the ribs 25^a.

A slot forming plate 31 has an opening 32 through it. This plate is placed over the projection 29. It has the side pins 33 which extend upwardly beyond the top 80 of the slot forming plate 31. These pins extend into openings 34 in a guide block 35. The guide block is slidingly mounted in a slot 36 in the top of the plate 17^a. It is held in its position in the slot by tongues 85 37 operating in grooves 38.

In operation the plates are assembled in a manner similar to the Allen patent but in setting up the plate 17^a the slot forming plate 31 is placed over the projection 29 90 and the guide block pushed down over the pins 33. Thus the guide block definitely locates and holds the plate 31 relatively to the projection 29. With this plate 17^a so assembled and the other lining plates in 95 position the material is placed in the mold as with the Allen structure and the mold is closed, the core acting on the inserted plastic material in the mold forcing it under very high pressure into all parts of the mold and 100 chilling it with some plastic materials, or heating it to vulcanize it where other material, such as when rubber, is used. As soon as the box becomes sufficiently hard the mold is stripped from the core and the lining stripped from the mold through the action of the push rod 15. The guide block 35 is then withdrawn, the plate 17^a is laid down, withdrawing the projection 29 from the opening 25 and the opening 32 in the 110

- slot forming plate 31. The slot forming plate can then be withdrawn from the box leaving a slot entirely around the opening 25 which slot extends through the top of 5 the box. With such a box the glass plate 28 may be dropped into place and the sealing material introduced around the slot and into the enlargements 27, thus completely closing the box with a transparent portion.
10. What I claim as new is:—
1. In a box mold, the combination of a mold plate; an opening forming projection on the plate; and a slot forming plate through which the projection extends.
  15. 2. In a box mold, the combination of a mold plate; an opening forming projection on the plate; a slot forming plate through which the projection extends; and a guide block secured to the plate and to 20 which the slot forming plate is secured.
  25. 3. In a box mold, the combination of a mold plate; an opening forming projection on the plate; a slot forming plate through which the projection extends; and a 25 guide block removably secured to the plate and to which the slot forming plate is secured.
  30. 4. In a box mold, the combination of a mold plate; an opening forming projection on the plate; a slot forming plate through which the projection extends; and a guide block secured to the plate and to which the slot forming plate is removably secured.
  35. 5. In a box mold, the combination of a mold plate; an opening forming projection on the plate; a slot forming plate through which the projection extends; and a guide block removably secured to the plate and to 40 which the slot forming plate is removably secured.
  45. 6. In a box mold, the combination of a mold plate; an opening forming projection on the plate; a slot forming plate through which the projection extends; and channel forming pins at the sides of the slot forming plate.
  50. 7. In a box mold, the combination of a mold plate; an opening forming projection on the plate; a slot forming plate through which the projection extends; channel forming pins at the sides of the slot forming plate; and a guide block into which the pins extend.
  8. In a box mold, the combination of a 55 mold plate; an opening forming projection on the plate; a slot forming plate through which the projection extends; channel forming pins at the sides of the slot forming plate; and a guide block slidingly 60 mounted on the plate and into which the pins extend.
  9. In a box mold, the combination of a mold having a mold cavity; a mold plate against the wall of the cavity; an opening 65 forming projection on the plate; and a slot forming plate through which the projection extends.
  10. In a box mold, the combination of a mold having a mold cavity; a mold plate 70 against the wall of the cavity; an opening forming projection on the plate; a slot forming plate through which the projection extends; and channel forming pins on the sides of the slot forming plate. 75
  11. In a box mold, the combination of a mold having a mold cavity; a mold plate against the wall of the cavity; an opening forming projection on the plate; a slot forming plate through which the projection extends; and a guide block movably secured 80 on the plate and to which the slot forming plate is secured.
  12. In a box mold, the combination of a mold having a mold cavity; a mold lining 85 formed of plates comprising a bottom plate and side plates, one of the side plates having an opening forming projection thereon; a slot forming plate through which the projection extends; a core adapted to enter the 90 assembled lining; and means for stripping the lining from the mold.
  13. In a box mold, the combination of a mold having a mold cavity; a lining plate in the mold having an opening forming projection therein; and means operating in connection with the projection forming a surrounding slot around the opening formed by the projection. 95
  14. In a box mold, the combination of a 100 side plate; means for completing the mold cavity; an opening forming projection on the side plate; and a slot forming means extending from the top of the mold cavity around the projection. 105

In testimony whereof I have hereunto set my hand.

PAUL H. HENKEL.
